CLAIM

The ornamental design for a nail polish bottle applicator cap, as shown and described.

DESCRIPTION

FIG. 1 is a perspective view of a nail polish bottle applicator cap;

FIG. 2 is a front view of the nail polish bottle applicator cap of FIG. 1;

FIG. 3 is a back view of the nail polish bottle applicator cap of FIG. 1;

FIG. 4 is a right side view of the nail polish bottle applicator cap of FIG. 1;

FIG. 5 is a left side view of the nail polish bottle applicator cap of FIG. 1;

FIG. 6 is a top view of the nail polish bottle applicator cap of FIG. 1;

FIG. 7 is a bottom view of the nail polish bottle applicator cap of FIG. 1; and,

FIG. 8 is an exploded perspective view of the nail polish bottle applicator cap of FIG. 1.

In the figures, portions drawn in broken lines do not form any part of the claimed design. The broken lines showing the bottle in FIGS. 1-8 illustrate portions of the nail polish bottle that form no part of the claimed design.

1 Claim, 5 Drawing Sheets
